PRESSING MACHINE

Angus F. Hanney, Norwood, Ohio, assignor to
 The American Laundry Machinery Company,
 Norwood, Ohio, a corporation of Ohio

Application March 15, 1937, Serial No. 130,962

5 Claims. (Cl. 38—25)

This invention relates to improvements in pressing machines and more particularly to such machines used for pressing garments and laundered articles.

Among the novel features of my invention is the provision of head and bed pressing members closed by power means and in which both of the pressing members and the essential parts of the power means are mounted on a portion of the frame so as to be swung away from the main or base portion of the frame, providing for easier assembly of new machines and easier repair of old machines.

Another feature of the present invention is the arrangement of the power means for causing press closure in very compact form with a minimum number of parts.

An object of the present invention is to provide a pressing machine for garments so that certain portions thereof may be pressed without mussing other parts of the garment. To this end the pressing bed and the supporting table thereunder are formed in such a manner as to allow the garment to hang smoothly when draped upon the pressing bed. Contributing to the same end the control members for the press closing power means are arranged in a novel manner on brackets above the pressing members.

Another novel feature of the invention is the provision of spring means for opening the press and a novel relationship of the spring connection with the power means which operates the press, whereby the spring is placed in position to cause an initial opening movement of the press-ing head.

Another feature of the invention is the novel connection of a motor with the head lever and with a toggle also connected with the head lever whereby the power means exerts a double effect, one acting directly on the head lever to move it toward closed position and the other acting on the toggle links to move the latter in toggle straightening direction, thus providing the final squeeze when the pressing members engage.

My invention also resides in the novel features disclosed in the drawings and described in the specification, and the essential features of which will be summarized in the claims.

In the drawings, Fig. 1 is a front elevation of my improved pressing machine showing in dash-dot lines a shirt dressed on the pressing bed; Fig. 2 is a top plan view of the machine of Fig. 1; Fig. 3 is a side elevation of the machine in open position with certain parts broken away to more clearly show the construction, the pressing head

being shown by dash-dot lines in safe closed position; Fig. 3a is a diagrammatic view of the control mechanism corresponding to the open position of the press in Fig. 3; Fig. 4 is a plan sectional view taken on the line 4—4 of Fig. 3; Fig. 5 is an elevational view similar to Fig. 3 showing the press closed; Fig. 5a is a diagrammatic view of the control mechanism corresponding to the position of the press shown in Fig. 5; while Fig. 6 is a side elevation of the machine with the main parts thereof swung away from the base portion of the frame.

I have illustrated one form of my pressing machine as embodying a frame having a base portion 10 and a movable table portion 11 hinged at 12 to the portion 10 so that the table 11 may be swung from the position of Fig. 3 or 5 to the position of Fig. 6. The movable portion 11 carries the pressing head and bed, the control mechanism and the power means, and when in the position of Fig. 6 all of these parts are more readily assembled on a new machine or more easily repaired in the case of an old machine.

While I have shown my invention applied to a press in which both the head and bed are movable, it will be understood that certain features are applicable to a machine in which only one of the pressing members is movable. In the present instance the pressing bed 13 has a downwardly extending sleeve 14 which embraces the cylindrical portion 15a of the member 15 which is secured to the table 11 and forms with the portion 11a of the table a servo-motor having a piston 16 secured to the sleeve 14 and arranged to be engaged and lifted by a diaphragm 17 beneath 35 which pressure fluid is supplied. A spring 18 biases the piston downwardly. A pin 19 prevents turning of the bed during its vertical movement.

The head 20 is secured at one end of the head lever 21 which is pivotally mounted at 22 intermediate its ends. The mounting 22 is between the bearing brackets 23 which are carried by the table 11. These brackets have forwardly extending stiffening webs 24 and laterally extending flanges 25 which are also connected to the rear edge of table 11 and form flanges for carrying the brackets which support the control mechanism. Flange plates 26 secure the steam connections 27 in place and suitable conduits 28 and 29 conduct steam to the pressing head. Other 50 conduits 30 carry steam to the pressing bed.

The power means for operating the pressing head comprises a cylinder and piston motor 31 carried by the table 11. The cylinder 31a is pivotally mounted at 32 on a pin carried by the 55

brackets 33 which are a portion of the table 11. The piston 31b is pivotally connected at 34 with a crank arm 35 which is rigidly fastened to a pin or shaft 36 rotatably mounted in the lower end of lever 21. A toggle comprising the links 37 and 38 connected together at the knuckle 39 is pivotally connected at the forward end by pin 32 to the frame and at the rear end by pin 36 to the head lever. In effect the cranks 35 and 37 form a bellcrank so that movement of crank 35 counterclockwise upon operation of motor 31 tends to move the toggle towards straightened position. At the same time the piston 31b exerts a direct rearward thrust on the lower arm of lever 21 to cause a rapid movement of the head 20 toward closed position. By having the crank arm 35 extending toward the pivot 22 the point 34 travels along very nearly a straight path during the operation of motor 31. This is due to the fact that point 36 describes an arc downwardly, while point 34 describes an arc upwardly about the point 36. Thus the resultant path of point 34 is very nearly in a straight line and reduces the wear of the piston in the cylinder of motor 31.

The movement of the head lever toward open position is limited by stop member 40 and the movement of the toggle as it reaches and passes slightly beyond straightened position as shown in Fig. 5 is limited by the shoulders 38' engaging 30 a stop member 41.

A spring 42 biases the head lever in open position. A very advantageous arrangement of this spring is provided by arranging a long spring within the base portion 10 of the frame having its lower end secured by a T-bolt 43 removably beneath a bracket 44 and having its upper end connected by a flexible member such as the chain 45 with a crank arm 46 rigid with pin 36. The chain passes over a sprocket 47 which is rotatably mounted on shaft 32. With this arrangement of the spring it exerts a direct pull on pin 36 when the head is open as shown in Fig. 3. The relationship between arms 35 and 46 is such that when the head is moved to closed position as shown in Fig. 5, the arm 46 is moved through substantially 45°, stressing spring 42 and at the same time providing a turning moment of the spring force about the point 36. It results from this arrangement of the parts that when the power means is released at the close of a pressing operation, the spring swings the link 37 of the toggle in toggle breaking direction, thus moving the toggle from its over-center position of Fig. 5.

A link 48 connects the toggle knuckle with a snubber mechanism 49 located in the base of the machine so as to properly snub both the opening and closing movements of the press. The control mechanism, as best seen in Figs. 3a and 5a, comprises valve casings 50 and 51 connected in series with a source of pressure fluid 52 and connected by conduit 53 with motor 31. Casing 50 houses a normally closed inlet valve 50a actuated by a manual 50b. Casing 51 houses a normally closed inlet valve 51a and a normally open outlet valve 51b, both on a common stem and operated by manual 51c. Conduit 54 connects the two valve casings in series. The power supply for servomotor 16—17 comprises conduit 55, valve casing 56 and conduit 57. Casing 56 houses a normally closed inlet valve 56a and a normally open outlet valve 56b mounted on a common stem and operated by manual 56c. Slidable along manual 56c is a detent 58 spring pressed toward the right as shown in Fig. 3a by spring 58a and adapted to engage beneath a portion 59 of the frame. When

5 manual 56c is depressed as shown in Fig. 5a the detent 58 engages frame portion 59 and holds the manual in its operated position. Upward movement of manual 56c moves the detent backwards because of the rounded nose thereof.

In order that laundered articles, such as shirts, coats and the like, may be pressed without mussing other portions of the garments, I have formed the frame and the work table or guard 60 so as to provide a smooth curve convex toward the 10 operator as shown at 60a, Fig. 2 and have arranged all other parts of the mechanism so that nothing projects at the front portion of the machine to disturb a garment depending from the pressing bed as shown in Figs. 1 and 2. For accomplishing this purpose and also because it is a 15 convenient location, I have mounted the control members for the power means above the pressing members on brackets 61 and 62. These brackets are bolted to the flange portions 25 of the table 11 20 and extended at the rear of the press upwardly and then forwardly. In bracket 61 is mounted the control member 51c. In bracket 62 are mounted control members 50b and 56c. The control members 50b and 51c are spaced apart greater 25 than the span of the operator's hand so that two hands must be used to supply power to motor 31. The manual 56c is close to the manual 50b so as to be actuated by the same hand of the operator.

The operation of the press is as follows: With 30 the press open, a garment is dressed on the pressing bed 13 and manuals 50b and 51c are depressed. This supplies pressure fluid from source 52 through valve casing 50, conduit 54, casing 51, conduit 53 to the forward end of cylinder 31a 35 which drives the piston and piston rod 31b rearwardly. The head lever is moved in a clockwise direction through the force of the piston acting by way of arm 35 on pin 36. At the same time rotary movement in a counterclockwise direction 40 is provided of cranks 35 and 37 moving the toggle finally to the position of Fig. 5, at which time the pressing head is in safe closed position as indicated in dot-dash lines in Fig. 3. At this time the operator depresses manual 56c, supplying 45 pressure fluid from source 52 through conduit 55, casing 56 and conduit 57 beneath diaphragm 17. This causes the piston 16 and bed 13 to be raised into contact with the head. This pressure of the bed against the head holds the toggle in the locked 50 position of Fig. 5 and motor 31 may be evacuated by releasing manuals 50b and 51c. The press remains closed until manual 56c is raised to the position of Fig. 3a, cutting off the supply of fluid beneath diaphragm 17. At such time spring 42 55 in the position of Fig. 5 will cause rotation of crank 46 and link 37 in a clockwise direction, breaking the toggle and permitting spring 42 to complete the opening of the press.

Two presses of the type described may be connected for tandem operation by providing a small servomotor 63 at each press in position to engage an arm 56d rigid with manual 56c. A conduit 64 is then extended from the servomotor at one press to a valve casing 65 at the other press. 60 Valve casing 65 contains a normally closed inlet valve 65a operable by a manual 65b. The casing is supplied with pressure fluid through a conduit 66. Preferably the manual 65b is mounted in bracket 61 alongside manual 51c. Thus 65 with press B in closed position the controls thereof will be in position corresponding to Fig. 5a. The operator at press A then depresses manual 65b admitting pressure fluid from source 52 through conduit 66, casing 65 and conduit 64 to 70 75

the servomotor 63 at press B, moving manual 56c thereof upwardly to cause opening of press B in a manner previously described.

It will be noted from Fig. 6 that by releasing 5 the T-bolt 43 from the bracket 44 and by disconnecting link 48 from the snubber, table 11 may be pivoted rearwardly about the point 12 carrying the pressing members, the power means and the control mechanism to the position of Fig. 6 for 10 better access to these parts. A pair of links 67-68 may be connected between the base portion 10 and the table portion 11 to limit this swinging movement of the table 11.

What I claim is:

15 1. In a pressing machine, a frame, upper and lower coacting pressing members mounted thereon for relative approach and separating movement of said upper member relative to said lower member, power means for causing said relative movement, and a control member for said power means mounted on a stationary portion of said frame above said pressing members.

20 2. In a laundry pressing machine, a frame, upper and lower coacting pressing members mounted thereon for approach and separating movement of said upper pressing member relative to said lower member, power means for causing said relative movement, said frame having a stationary bracket portion extending over said 25 pressing members, a table below the lower of said pressing members having its forward peripheral edge formed as a smooth curve convex toward the operator, and a control member for said power means mounted on said bracket portion.

30 35 3. In a pressing machine, a frame having a table portion pivotally mounted on a base portion, a pressing bed mounted on said table portion, a lever pivotally mounted intermediate its

ends at the rear of said table portion, a pressing head at one end of said lever and movable thereby toward and from said bed, and a fluid motor having cylinder and piston members, one member connected with the other end of said lever and 5 the other member carried on the lower face of said table portion, whereby when said table portion is moved about its pivot said motor is exposed for inspection and repairs.

4. In a pressing machine having coacting head 10 and bed pressing members, a frame having a table portion pivotally mounted on a base portion, power means for causing pressing action between said pressing members, and said power means being mounted on the lower face of said 15 table portion, whereby when said table portion is moved about its pivot said power means is exposed for inspection and repairs.

5. In a pressing machine, a frame having a table portion, a pressing bed mounted on the 20 upper face of said table portion, a lever pivotally mounted intermediate its ends on said table portion, a pressing head at one end of said lever and movable by lever oscillation toward and from said bed, the other end of said lever extending below 25 said table portion, a toggle connected between said other end of said lever and said table portion, said toggle when straightened to move said head adjacent said bed being substantially parallel to said table portion, a crank arm rigid 30 with one of the members of said toggle, a fluid motor having cylinder and piston members, one member connected with said crank arm and the other member carried on the lower face of said table portion, and said motor having a power 35 stroke substantially parallel to said table portion.

ANGUS F. HANNEY.
